(57) **CLAIM**

The ornamental design for a lighting fixture having struts, as shown and described.

DESCRIPTION

FIG. 1 is a top plan view of a lighting fixture having struts according to an embodiment of the invention;

FIG. 2 is a top perspective view of the lighting fixture illustrated in FIG. 1;

FIG. 3 is a front elevational view of the lighting fixture illustrated in FIGS. 1 and 2;

FIG. 4 is a right side elevational view of the lighting fixture illustrated in FIGS. 1-3, the left side being the mirror image thereof;

FIG. 5 is a back elevational view of the lighting fixture illustrated in FIGS. 1-4;

FIG. 6 is a bottom plan view of the lighting fixture illustrated in FIGS. 1-5; and,

FIG. 7 is a bottom perspective view of the lighting fixture illustrated in FIGS. 1-6.
